UNITED STATES PATENT OFFICE.

ELIJAH R. HILL, OF NEW ALBANY, MISSISSIPPI.

FLUSH-TANK VALVE.

1,257,231.

Specification of Letters Patent. Patented Feb. 19, 1918.

Application filed February 28, 1917. Serial No. 151,436.

To all whom it may concern:

Be it known that I, ELIJAH R. HILL, a citizen of the United States, and resident of New Albany, in the county of Union and State of Mississippi, have invented a new and Improved Flush-Tank Valve, of which the following is a full, clear, and exact description.

This invention relates to baths and closets and has particular reference to flush tank apparatus.

Among the objects of this invention is to provide a new and useful type or design of inlet valve for any suitable or standard water closet flush tank or its equivalent.

More definitely stated by this improvement I have succeeded in producing an automatically controlled inlet valve of maximum simplicity and reliability, and one which if it becomes out of order may easily and cheaply be repaired.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical sectional view of my improved device shown as applied to a flush tank, and

Fig. 2 is a transverse sectional detail on the line 2—2 Fig. 1.

Referring now more particularly to the drawings I show one preferred embodiment of the invention, subject to such variations or modifications as fairly fall within the scope of this specification. As shown, my improvement comprises a bracket 10 including a base 11 from which projects downwardly a spud 12 through the bottom of the tank 13, the bracket and spud being locked rigidly and tightly in position in any usual manner as by means of a nut 14 threaded upon the spud, and the upper end of an inlet or supply pipe 15 is connected to the spud as by means of a coupling 16. The bracket also includes a pair of upwardly projecting standards 17 and 18 arranged preferably on opposite sides of the base 11. The base is provided with a central threaded socket 19

at the lower end of which is formed a shoulder 20.

The valve mechanism includes a nozzle 21 having a threaded boss 22 fitted into the socket 19 and provided preferably with a base flange 23 abutting against the upper surface of the base 11. Said nozzle is formed with a central bore 21' formed in alignment with the axis of the spud bore 12'. The upper end of the nozzle constitutes the valve seat and the outer surface of the nozzle is so constructed as to consist of two different sizes of cylindrical portions, the larger of which is indicated at 24, while the smaller is indicated at 25.

The movable portion of the valve comprises a sleeve 26 of tubular construction but having larger and smaller cylindrical portions 26^a and 26^b co-operating respectively with the larger and smaller portions of the nozzle. The two different sized portions of the sleeve are spaced equally from the respective portions of the nozzle which they surround, providing a passageway 27 through which the water is adapted to flow from the supply pipe into the tank. The outlet thus provided for the water from the valve being directed downwardly toward the bottom of the tank practically and in a simple manner eliminates all splashing and noise commonly incident to the rush of the water. The upper end of the sleeve portion 26^b is externally threaded to receive a cap 28 between which cap and the upper end of the sleeve is fitted any suitable type of gasket or washer 29. The periphery of the washer being gripped between the cap and the end of the sleeve is held in fixed position with respect to the other parts of the valve and in position to seat squarely upon the aforesaid valve seat. Between the sleeve and the nozzle extend a plurality of lugs 30 which span the space 27 and serve to hold the sleeve properly spaced from and concentric with the nozzle. These lugs 30 may be carried by either of these parts and project toward and into contact with the other. As indicated they are made as integral parts of the sleeve.

At 31 I indicate a yoke shown as in the nature of an open loop, the two free ends of which are applied to opposite sides of the upper end of the standard 17 and through which is passed a pivot pin 32. That portion of the yoke diametrically opposite the 110

pivot consists of a lug 33 to which is pivoted a link 34 by means of a pivot pin or bolt 35. The two side portions of the yoke extend on opposite sides of the sleeve 26 and preferably spaced slightly therefrom to insure freedom of movement. I provide, however, pin and slot connections between the yoke and the sleeve whereby movement of the yoke in either direction will cause endwise movement of the sleeve. According to the illustration the pins or lugs 36 are formed as integral parts of the sleeve and project radially outwardly therefrom into the slots 37 formed in the side portions of the yoke, with the longer dimensions of the slots transverse to the direction of movement of the sleeve.

A bell crank 38 is pivoted at 39 upon the upper end of the standard 18, the shorter arm of the bell crank extending horizontally toward the valve mechanism and being pivotally connected at 40 with the upper end of the link 34. The ball float 41 is rigidly but adjustably connected by any suitable means well known in the art to the upper end of the bell crank.

When the water is withdrawn from the tank by any suitable means with which this particular invention is not directly concerned, the float ball 41 drops with the water as usual swinging the bell crank around its pivot 39 and the weight of the ball serves to lift the yoke 31 swinging it upwardly around its pivot 32, as indicated in dotted lines in Fig. 1. This upward movement of the yoke causes through the lug and slot connections 37 the upwardly unseating movement of the valve sleeve 26 allowing the water to flow upwardly through the nozzle whence it is deflected downwardly through the space 27 refilling the tank and causing the lifting of the ball float whereby when the level of the water reaches the predetermined plane the positive seating of the valve washer 29 is effected. If desired any suitable form or construction of strainer 42 may be interposed in the inlet mechanism as for example in the upper end of the spud where the periphery of the strainer is gripped between

the lower end of the boss 22 and the shoulder 20. A strainer of this character serves to prevent any solid particles such as sand, scale, grit or the like from destroying prematurely the washer 29. I also indicate at 43 a suitable refilling tube carried by the sleeve and communicating with the space 27 55 therein.

I claim:

1. In valve mechanism for flush tanks, the combination of an upwardly projecting inlet nozzle whose upper end constitutes a 60 valve seat, said nozzle comprising a plurality of coaxial tubular cylindrical guide portions of different diameters, a valve coöperating with said seat and comprising a sleeve projecting downwardly over said nozzle and 65 having a plurality of cylindrical tubular portions spaced equally from the respective tubular portions of the nozzle and means to automatically control the position of the valve, said valve also including a cap carrying a gasket and removable from the upper end of the sleeve without disturbing any other part of the device.

2. In a flush tank valve, the combination of a rigid base having a central threaded 75 socket and a pair of upwardly projecting standards on opposite sides thereof, a nozzle having a boss removably fitted into said socket and supported thereby rigidly upon the base, the opposite end of the nozzle constituting a valve seat, a strainer held in the socket between the base and the nozzle, a sleeve fitted in spaced relation over said nozzle and having an open end adjacent to the base, the opposite end of the sleeve being 80 sealed and coöperating directly with said seat, and an elliptical yoke pivoted at one end to one standard and surrounding said sleeve, said sleeve having laterally projecting studs and the yoke having slots into 85 which the studs project, and means connecting the other end of the yoke to the other standard for controlling the position of the sleeve with respect to the nozzle.

ELIJAH R. HILL.
